VALVE FOR ROCK DRILLS

Filed Aug. 27, 1930

UNITED STATES PATENT OFFICE

EDWARD F. TERRY, OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed August 27, 1930. Serial No. 478,107.

This invention relates to rock drills, but more particularly to a valve for fluid actuated rock drills of the hammer type.

A few of the objects of the invention are 5 to obtain a quick and positive action of the valve and to assure a heavy blow of the hammer piston against the working implement.

Other objects will be in part obvious and in part pointed out hereinafter, and to all 10 of these ends the invention consists of the combination of elements, features of construction and arrangement of parts having the general mode of operation substantially as hereinafter described and claimed and 15 illustrated in the accompanying drawings, in which.

Figure 1 is a longitudinal sectional elevation of a rock drill equipped with a valve 20 constructed in accordance with the practice of the invention and showing the valve in position for admitting pressure fluid into the piston chamber to drive the piston on its working stroke, and

Figure 2 is a similar view showing the 25 valve in position to admit pressure fluid into the opposite end of the piston chamber for returning the piston.

Referring more particularly to the drawings, A designates generally so much of a rock 30 drill as will serve to illustrate the invention and comprises a cylinder B at the rear end of which is arranged a back head C.

Within the cylinder B is a piston chamber D having in this instance a free exhaust 35 port E which is controlled by a hammer piston F reciprocable in the piston chamber D. The hammer piston F may be of a conventional type having a head G and a forward extension or stem H to extend slidably 40 through a closure J, as for instance, a front head for delivering blows to a working implement (not shown) but which may extend into the front head J and be guided thereby in a well known manner.

In the rear end of the cylinder B is an enlarged bore K to receive, among other elements, rotation mechanism comprising in 45 this instance a fluted rifle bar L which extends into the cylinder to interlock with a rifle nut O threaded into the head G of the

piston F. The rifle bar L is provided with the usual head P which is arranged within a rotation ratchet Q in the bore K and acting in this instance as a seat for the back head C.

The rotation ratchet Q is provided with 55 the usual introverted teeth R to act as abutments for spring pressed pawls S carried by the head P.

The back head C may be secured to the cylinder B in any suitable manner, as for 60 instance, by the usual spring pressed side bolts (not shown) and said back head in this instance forms a housing for a throttle valve T having a central chamber U which may be in constant communication with a source 65 of pressure fluid supply. In the wall of the throttle valve T is a port V which, in the open position of the throttle valve, registers with a passage W in the back head and leading to a supply reservoir X also in the back head. 70

Interposed between the rotation ratchet Q and the rear end of the piston chamber D for which it forms a closure is a valve chest Y comprising an inner or plug member Z and an outer encircling ring member b. 75 The plug member Z has a bore o therethrough to receive the rifle bar L and carries a lateral flange d which seats against a shoulder e at the juncture of the piston chamber D and the bore K.

Immediately rearwardly of the flange d and forming a part of the plug member Z is a boss f which extends into a bore g of the ring member b for centralizing the members Z and b with respect to each other at their 80 forward extremities. Adjacent the boss f and forming a part of the plug member Z is a reduced portion h and rearwardly thereof and also forming a part of the plug member Z is a portion j of minimum diameter which 85 extends into a bore k in the rear end of the ring member b to assist in centralizing the members Z and b with respect to each other.

Within the ring member b is a bore which 90 cooperates with the portions h and j of the plug member Z to form a valve chamber o for the reception of a distributing valve p of the sleeve type whereby the distribution of pressure fluid to the ends of the piston chamber D is effected. 100

The pressure fluid utilized for actuating the piston is conveyed in this instance to an annular groove *q* in the ring member *b* and opening into the valve chamber *o* near the 5 front end thereof, and from the annular groove *q* leads a supply passage *r* which extends rearwardly through the ring member *b* and the rotation ratchet *Q* to communicate with the supply reservoir *X*.

- 10 Leading from the front end of the valve chamber *o* and extending through the flange *d* is a rear inlet port *s* which opens into the rear end of the piston chamber *D*. The pressure fluid for the front end of the piston 15 chamber *D* is conveyed thereto by a front inlet passage *t* which opens with its inlet end or port *u* into the valve chamber *o* preferably immediately rearwardly of the annular groove *q*. The inlet passage *t* may also serve 20 to convey compression from the front end of the piston chamber *D* and in order to provide a passage for such compression to the atmosphere the valve *p* is provided with a neck *v* to establish communication between 25 the inlet passage *t* and an atmospheric passage *w* leading from the valve chamber *o* to the atmosphere at a point rearwardly of the port *u*.

At the front end of the valve *p* is an external lateral flange *x* which, during the reciprocations of the valve, moves across the groove *q*. The front end of the flange constitutes a pressure area *y* which overlies the rear inlet port or ports *s* so that compression 35 formed in the rear end of the piston chamber *D* may act against the pressure area *y* to shift the valve rearwardly and thus open communication between the groove *q* and the inlet passage or passages *s*. On the opposite 40 or rear end of the flange *x* is a pressure area *z* of smaller area than the pressure area *y* and said pressure area *z* is constantly exposed to pressure fluid in the groove *q*, both to assist in throwing the valve and to hold the valve *p* immovable during the admission of pressure 45 fluid to the front end of the piston chamber *D*.

Located at the rear end of the valve *p* is an introverted flange *2* the front end *3* of which constitutes a seating surface adapted 50 to seat upon a shoulder *4* at the juncture of the portions *h* and *j* of the inner member *Z* to limit the forward movement of the valve *p*.

At the rear end of the valve *p* is a seating surface *5* which is adapted to seat against the 55 rear end wall of the valve chamber *o* to limit the rearward travel of the valve. The rear surface of the flange *2* is in this instance provided with a shallow recess *6* into which pressure fluid from the rear portion by the piston chamber *D* may be conveyed by a kicker passage *7* in the cylinder *B* and the outer member *b* to assist the pressure fluid constantly 60 acting against the pressure area *z* for throwing the valve forwardly. The kicker passage *7* opens into the piston chamber *D* at a

point slightly rearwardly of the exhaust port *E* and like the exhaust port *E* is also controlled by the piston *F*.

Preferably a small leak port *8* is formed 70 in the flange *2* to provide an immediate escape for a portion of the pressure fluid admitted into the recess *6* which, as will be readily observed, constitutes an actuating surface. By forming the port *8* in the flange *2* the pressure fluid admitted into the recess *6*, or at least 75 a portion thereof, may immediately escape through an atmospheric vent *9* formed in this instance in the plug member *Z* and in the cylinder *B* and being in constant communication with the port *8*. The pressure fluid 80 thus escaping through the port *8* maintains the vent *9* and thus the shoulder *4* free of such dust and dirt which might otherwise impede the action of the valve or cause it to short-stroke. 85

The operation of the device is as follows: 90 With the valve *p* and the piston *F* in the positions illustrated in Figure 1 pressure fluid will flow from the groove *q* through the rear inlet passage or passages *s* into the rear end of the piston chamber *D* to drive the piston *F* forwardly on its working stroke. During such admission of pressure fluid into the rear end of the piston chamber the pressure fluid will act against the pressure area *y* and maintain the valve *p* immovable in its rearmost position. As the piston *F* proceeds forwardly the kicker passage *7* will be uncovered thereby. Pressure fluid will then flow into the recess *6* and, together with that pressure fluid acting against the pressure area *z*, will move the valve *p* forwardly. This movement of the valve *p* will take place at about the instant the piston *F* uncovers the exhaust port *E*. 100

The pressure fluid used for impelling the piston *F* forwardly together with the pressure fluid remaining in the recess *6* will then be exhausted to the atmosphere, it being understood of course that the pressure within the recess *6* will have been previously reduced in value due to the escape of a portion thereof through the leak port *8* and the atmospheric vent *9*. 105

Upon movement of the valve *p* to the new position and the simultaneous delivery of the blow of the hammer piston against the working implement pressure fluid will flow from the groove *q* across the pressure area *z* against which it acts to hold the valve *p* stationary 110 in the front end of the valve chamber, thence flows through the front inlet passage *t* to return the piston *F* to its initial position. 115

The air compressed in the rear end of the piston chamber *D* after the piston *F* covers the exhaust port *E* and the kicker passage *7* will act against the pressure area *y* to again 120 return the valve to its initial position.

During the forward stroke of the piston 125 the air in the front end of the piston chamber *D* at a

ber D will be forced therefrom through the inlet passage *t*, the neck *v* in the valve and through the atmospheric passage *w*, so that during the working stroke of the piston its movement will not be in any way retarded by compression which, if unrelieved, would cushion the blow of the hammer piston F.

I claim:

In a fluid actuated rock drill, the combination of a cylinder having a piston chamber and a piston therein, an exhaust port in the cylinder controlled by the piston, a valve chest having a valve chamber and a supply passage, inlet passages leading from the valve chamber to the piston chamber, a valve in the valve chamber having a flange at its front end movable across the supply passage for controlling the flow of pressure fluid to the inlet passages, a pair of opposed differential pressure areas on the flange, the larger of said pressure areas being subjected to compression for throwing the valve into a position to admit pressure fluid into the rear end of the piston chamber and being subsequently subjected to live pressure fluid for holding the valve in such position, the smaller of said pressure areas being constantly exposed to pressure fluid tending to move the valve to a position for admitting pressure fluid into the front end of the piston chamber and for holding the valve in such position, an introverted flange on the rear end of the valve having front and rear seating surfaces, said rear seating surface constituting an actuating surface intermittently subjected to pressure fluid valved by the piston to assist the pressure fluid acting against the smaller pressure area in throwing the valve, a vent in the valve chest for subjecting the front seating surface to atmospheric pressure, and a passage in the introverted flange to intermittently pass pressure fluid through the vent for preventing the entrance of foreign matter into the vent.

In testimony whereof I have signed this specification.

EDWARD F. TERRY.
